GOLF PUTTER HEAD

Roy A. Hemsoth, 4333 Winter St.,
Fort Wayne, Ind. 46806

Filed Jan. 28, 1969, Ser. No. 15,545

Term of patent 14 years

Int. Cl. D21—03

U.S. Cl. D34—5

FIG.1

FIG.3

FIG.5

FIG.2

FIG.4

FIG.6

FIG.7

FIG. 8

FIG. 9

FIG. 1 is a front elevational view of a golf putter head showing my new design, the rear elevational view of the same golf putter head appears identically thereto;

FIG. 2 is a top plan view thereof;

FIG. 3 is a front elevational view of a modified form of my design for a golf putter head illustrated in FIGS. 1 and 2, the rear elevational view of the same putter appears identical thereto;

FIG. 4 is a top plan view of my design illustrated in FIG. 3 wherein the modification may be seen, namely, a depressed sight line;

FIG. 5 is a front elevational view of a second modified form of my design for a golf putter head illustrated in FIGS. 1 and 2, the rear elevational view of the same putter appears identically thereto wherein the blade is narrower;

FIG. 6 is a top plan view of my design illustrated in FIG. 5;

FIG. 7 is a side view of my designs illustrated in FIGS. 1 and 2 and FIGS. 5 and 6;

FIG. 8 is a side view of my design illustrated in FIGS. 3 and 4; and

FIG. 9 is a perspective view showing my design illustrated in FIGS. 1 and 2.

The fragmentary broken line showing of a shaft is for illustrative purposes only.

I claim:

The ornamental design for a golf putter head, as shown and described.
